(57) **CLAIM**

The ornamental design for a “power supply control device,” as shown and described.

DESCRIPTION

FIG. 1 is a perspective view of a power supply control device showing the new design;

FIG. 2 is a front view of the power supply control device of FIG. 1;

FIG. 3 is a rear view of the power supply control device of FIG. 1;

FIG. 4 is a left side view of the power supply control device of FIG. 1;

FIG. 5 is a right side view of the power supply control device of FIG. 1;

FIG. 6 is a top view of the power supply control device of FIG. 1; and,

FIG. 7 is a bottom view of the power supply control device of FIG. 1.

The broken lines shown represent the portions of the power supply control device that form no part of the claimed design.
